(54) **SPINNG, SPEEDER, DOUBLE**

(76) Inventor: **William Field**

William Field, of North Providence State of Rhode Island,
Letters Patent.

The schedule referred to in these Letters Patent and making part of the same
containing a description in the words of the said William Field himself of
his improvement in a machine called the double Speeder.

To all to whom these presents shall come,

Be it known that I William Field of North Providence in the County of
Providence and State of Rhode Island, and Providence Plantations, have
invented and made a new and useful improvement in the machine called
the Double Speeder used for making roving in the manufacture of cotton
and the following is a full and exact description of the same,

It consists in a plan of compressing the roving on the spool so hard or
compact that the same quantity may be put on a spool of only one fifth of
the common size. A machine with the improvement will occupy only one
half of the room, will require much less power, and will run at least one
third faster than common Speeder. I have retained in connection with my
improvement the usual place of drawing, twisting and winding the roving,
except the difference of running the spools faster than the flyers to take up
the roving instead of permitting them to fall back, sufficient to effect the
same thing as in the common manner.

The flyer is about one half the usual length and diameter and
is supported wholly at the top and has a hoop at the lower end of the arms
to prevent them from expanding when in operation. The roving passes from the
rotary through the nose of the flyer and the arms to the spool.

By the application of my improvement the roving is conducted on the
spools by pressing against its surface, a thin circular plate about the di-
ameter of the flyer which receives a rotary motion from the friction of the
spool, the plate may be as thick as the traces motion of the spool will

about, between the lower head of the spool when up, and the bottom of the flyer, leaving sufficient space between the plate and the bottom of the flyer for the roving to pass round, as it winds on the spool. The plate for each spindle in a machine runs on an upright rail that stands in a rail placed in the rear of the spindle; the rail is supported by stands at each end on which it will slide backward and forward very easily at right angles with the spindle. The circular plates are placed on this rail with their surfaces all on a line. By sliding the rail which is done by a spring or weight up to the spool the edges of the plates will press constantly on the roving and equally on all the spools. The roving in this manner is compressed to almost any extent. As the spools increase in size by the winding on of the roving the rail moves back from the spindle, by the pressure of the edges of the plates on the spools. Connected with this, is another important motion, the cones in the machine having my improvement, are belted and the guides that move the belt is operated altogether different from those in other spindles. I cause it to move by a weight or spring and its motion is governed by the filling of the spools. In other spindles there is no other connection between the filling of the spools and the motion of the belt guide. To produce this operation I have placed on the guide a cycloid rack, I have also between the rail before described and a rack placed a lever one edge of which is made to catch in the rack and frequently is moved by the weight of a spring faster than the spool fills and requires the movement to graduate its motion. As the spools fill the rail moves back the lever attached to it moves out of the rack, and the belt guide is drawn forward by the spring or weight. In this way the spool graduates its own motion so as to take up the roving uniformly from the commencement of the filling of the spool to its completion. There may be various modes of connecting the filling of the spools with the motion of the belt guide, I claim as part of ~~my~~ my improvement the connection generally. I have also applied a different form of ~~hast~~ to raise and fall the spools, on the common spindles ~~hast~~ the rise and fall are equal, that is the rise is no quicker than the fall on a spindle with my improvement, the hast is calculated to raise the spool faster than it falls in

order that a less quantity of roving may be deposited when the spool is rising, it being necessary on account of the circular plate not acting directly on the concave which the spool receives when rising, but acting on both concavities when the spool is falling.

1st what I claim as my improvement and not previously known is the plan of compacting roving on spools by circular plates, and having a rotary motion acquired by their pressure on the spools, the edge of which rest on the roving as it is received from the flyers, and thereby condense it so that a much greater quantity can be deposited on spools of the usual size: 2nd The sliding rail in the rear of the spools on which the circular plates are placed and the connection between the increasing size of the spools, and the transverse motion of the belt guide so that the spools may cause the variation of speed which their constantly increasing size requires. 3rd The application of a heart, for transferring the spools so formed as to cause them to rise with a greater velocity than they fall, so that a less quantity of roving may be deposited on the spools when rising than when falling.

North Providence, August 27. 1838.

William Field

N. B. The model accompanying this specification is not intended to represent an entire machine but those parts only which are generally connected with my improvement
